CLAIM

The ornamental design for a handle for cooking utensil, as shown and described.

DESCRIPTION

FIG. 1 is a perspective view of a handle for cooking utensil, showing my new design;

FIG. 2 is a side elevational view thereof;

FIG. 3 is a top plan view thereof;

FIG. 4 is a bottom plan view thereof;

FIG. 5 is an enlarged view thereof from the right of FIG. 3; and,

FIG. 6 is a further enlarged view thereof from the left of FIG. 3.
